(Cl. D74—17)

To all whom it may concern:

Be it known that we, Melven V. Nelson and Garfield L. Beckstrom, citizens of the United States, residing at Chicago, in the county of Cook and State of Illinois, have invented a new, original, and ornamental Design for Ball Point Pen or Similar Article, of which the following is a specification, reference being had to the accompanying drawing, forming a part thereof.

In the drawing:

Figure 1 is a front elevational view of a ball point pen or similar article embodying our new design and with the cap covering the writing end;

Fig. 2 is a side elevational view of the same with the cap separated and uncovering the writing end; and

Fig. 3 is a rear elevational view thereof and arranged for writing.

Our design for a ball point pen is characterized by the barrel and the cap being of substantially the same diameter and contoured so that when the same is in either an open position or a closed position the cap merges into the barrel and gives an appearance of a continuous and unbroken outline, all essentially as illustrated.

We claim:
